(57) **CLAIM**

The ornamental design for a bathtub, as shown and described.

DESCRIPTION

FIG. 1 is a perspective view of a bathtub having a shell with a head recess defined in the bathtub shell;

FIG. 2 is a right side elevation view thereof, the left side being a mirror image thereof;

FIG. 3 is a top plan view thereof;

FIG. 4 is a rear elevation view thereof;

FIG. 5 is a front elevation view thereof; and,

FIG. 6 is a bottom plan view thereof.

The parts shown in dotted lines form no part of the invention.

The broken line showing of a bath tub basin are included for the purpose of illustrating a portion of the shell with head recess that forms no part of the claimed design.
